UNITED STATES PATENT OFFICE.

CLYDE M. DAWDY, OF BOONE, IOWA.

AUXILIARY CARBURETOR.

Application filed January 7, 1925. Serial No. 1,096.

To all whom it may concern:

Be it known that I, CLYDE M. DAWDY, a citizen of the United States, residing at Boone, in the county of Boone and State of Iowa, have invented certain new and useful improvements in an Auxiliary Carburetor, of which the following is a specification.

This invention has for its object, broadly, to provide an oil or gasoline driven engine with an auxiliary carburetor adapted to deliver to the intake manifold a mixture of vapors and gases obtained from two sources, one from the crank case by communicating with the breather tube of same, the other including moisture and air from the radiator, the vapors being delivered to and treated by the auxiliary carburetor before delivery to the intake manifold.

The two vapors thus combined and mixed by the herein described device form a combustible mixture and is added to the gaseous mixture of the conventional carburetor of the engine, and on account of the construction now provided the fuel mentioned is thoroughly broken up and mixed in a manner to render it more favorable for combustion, thereby to obtain a more uniform power and flexibility for the engine, and tending to prevent carbon deposits.

Another object is to provide a device for the purposes mentioned which will consist of few and simple parts and which may be readily applied to any engine of ordinary construction without interfering with the working parts thereof.

A further object is to provide an auxiliary carburetor of such construction that the intake manifold will receive therefrom a flow of heated and vaporized oil to be controlled by suction of the engine. The invention includes the use of an upright slide-valve operated by the suction mentioned, and adapted to remain on its seat while the engine is idling and thereby conserving fuel.

With the foregoing objects in view and others to be mentioned the invention presents a novel and useful construction, combination and arrangement of parts as described herein and claimed, and as illustrated in the accompanying drawings, it be-

ing understood that changes in form, size, proportion of parts and minor details may be made, said changes being within the scope of the invention as claimed.

In the drawings, Fig. 1 is a side view of an automobile provided with the device. Fig. 2 is a view in longitudinal section of a two-part construction for the auxiliary carburetor. Fig. 3 is a side view showing a part of a gas engine provided with the device. Fig. 4 is a view in longitudinal section of the auxiliary carburetor. Fig. 5 is a transverse section on line 5—5 of Fig. 4, the view being on an enlarged scale. Fig. 6 is a side view of a slide-valve. Fig. 7 is a side view of a compartment for the upper part of the device. Fig. 8 is a side view of a compartment for the lower part of the device. Fig. 9 is a bottom plan view of the compartment shown in Fig. 7. Fig. 10 is a transverse section on line 10—10 of Fig. 8. Fig. 11 is a sectional view on line 11 of Fig. 6. Fig. 12 is a transverse section through the lower compartment on line 12—12 of Fig. 10.

The present invention is shown and described in connection with a conventional carburetor 1 and the intake manifold 2 of a gasoline engine, also in connection with the overflow pipe 3 of a radiator 4, and the breather-pipe 5 of a crank-case 6 of said engine. In the drawings, like characters indicate like parts in the several views.

In order that the objects first mentioned may be attained, I provide parts for an auxiliary carburetor which may consist of the upright, cylindrical casing 7 shown in Fig. 4, and parts therein and connected therewith, and these will first be explained.

Numeral 8 indicates a cylindrical receptacle adapted to be secured, preferably by a threaded connection, in the upper end of the casing 7, said receptacle being provided with an inner, annular chamber 9 and an outer annular chamber 10, and having its bottom provided with apertures *a* as clearly shown in Figs. 4, 5 and 9, apertures *b* being formed in the partition 11 so that the compartments 9 and 10 will be in communication.

Numeral 12 indicates a cylindrical recep-

tacle adapted to be secured in the lower end of the casing 7, said receptacle being provided with an inner and an outer chamber respectively indicated at 13 and 14, the partition 15 between said chambers being provided with numerous apertures *c*. In the upper wall of the chamber 13 and centrally thereof is provided a seat *d* for a needle valve having a stem 16 threaded in the top 10 of the receptacle 8, and adapted to be under control of a lock-nut 17.

Numeral 18 indicates a compartment formed in the upper part of the receptacle 12 adapted to communicate with the chamber 13 subject to the control of the needle valve; and the top or upper end of the cylindrical receptacle 12 is provided with apertures *e*.

Numeral 19 indicates a comparatively long chamber in the casing 7, said chamber 19 being disposed between the receptacles 8 and 12. I provide an elongated, hollow slide-valve 20, its top *f* and bottom *g* being of disc-form with diameters slightly less than 25 the diameter of the bore of the casing 7, and it will be understood that this valve may have upward sliding movements caused by suction of the engine, its top *f* engaging the bottom of the receptacle 8 when said valve 30 moves upwardly, and its bottom *g* engaging the top of the receptacle 12 when moving downwardly, these engagements being in alternation.

It will be noted that, to avoid friction, this 35 valve is approximately of concave form, between its ends, the only parts which may loosely engage the walls of the casing 7 being the parts *f* and *g*. Numeral 21 indicates a by-pass traversed by the stem 16 of the 40 needle valve, said by-pass being at all times in communication with the elongated chamber 19 on account of the apertures *h* and *k* which are formed in the sides of the valve, the bottom *g* preferably being imperforate, 45 and the top *f*, at its middle, being provided with an aperture *m*.

Numeral 22 and 23 indicate intake pipes for the chamber 14, the pipe 22 having a branch *n* communicating with the breather tube 5 of the crank case 6, and having a branch *p* communicating with the overflow pipe 3 of the radiator 4, the pipe 23 operating to furnish a suitable supply of gasoline 50 or similar element to said chamber 14, subject to the control of a valve 26, and in operation the gasoline may be used or may be dispensed with, depending upon requirements and conditions. Numeral 24 indicates a discharge pipe provided for the 55 chamber 10 and which communicates with the intake manifold.

As thus described the parts are very effective for mixing the vapors from the crank case and radiator and also gasoline, and for 60 automatically discharging the mixture to the

intake manifold, said vapors becoming thoroughly mixed in said manifold with the mixture coming thereto from the carburetor 1, this last named mixture being effectively broken up to be delivered, jointly with the 70 vapors thus mixed by the present device, to the engine cylinders in a manner to effect uniformity of power and flexibility of the engine.

It will be seen that vapors from the crank 75 case and radiator are first joined in the intake pipe 22, both vapors generally being in a heated condition, and after entering the chamber 14 they pass through the perforations *c* and must pass the seat of the needle 80 valve in order to enter the chamber 19 by passing through the apertures *e* when the slide valve 20 moves upwardly by operation of the suction mentioned.

When the valve 20 slides upwardly, the 85 mixture above the base *g*, or the greater part of said mixture, will be carried upwardly and will pass through the comparatively small apertures or perforations *a* into the chamber 9, and will be discharged through 90 the pipe 24 to the intake manifold by passing through the apertures *b*. It will thus be seen that, on account of the construction, the vapors will become thoroughly mixed before entering the intake manifold. 95

By referring to Fig. 5 it will be seen that when the upper end of the slide valve engages the bottom of the receptacle 8 said part *f* will cover approximately one-half of the areas of the apertures *a*, this being a desired feature for causing a still further mixing of the vapors by operation of suction, and being effective for that purpose for the reason that suction will continue after the slide valve has moved upwardly into engagement with said receptacle 8 and while the apertures *a* are partly covered. 100

It is understood, of course, that an upward movement of the slide valve tends to draw the vapors from the crank case and radiator 110 into the several chambers 14, 13, and 18 and into the lower part of the chamber 19 by passing through the several apertures *c* and *e* and valve seat *d*, and when the slide valve moves downwardly the mixed vapors thus 115 contained in that part of chamber 19 below said valve, will move upwardly through the by-pass 21 and through the limited annular area *x* between the members *f* and *g* and the adjacent walls of the cylindrical casing 7, this limited area permitting a free downward movement of the slide valve. 120

In some instances a two-part auxiliary carburetor, illustrated in Fig. 2 of the drawings, is of advantage, and since the parts for this construction are the same as already described, a description in detail thereof is not considered necessary except to state that the chambers 14 of the cylindrical casings 7 are in communication by means of a pipe 23' 130

provided with an intake pipe 25 to permit gasoline to enter subject to the control of a valve 26.

Also, in this two-part construction, the 5 chamber 14 of each cylindrical casing 7 is provided with an intake pipe 22 having branches n' and p' adapted to communicate respectively with the breather-pipe 5 of the crank case and overflow pipe 3 of the radiator. Also, in this two-part construction, a 10 pipe 24' communicates with each chamber 10 of a cylindrical casing 7, said pipe 24' being provided with a conducting pipe 27 adapted to communicate with the intake 15 manifold.

While in the drawings I have shown my improvements in connection with gas engines for automobiles, it is obvious that the same may be applied to gas engines generally; and since operation is the same I may employ a single casing or two or more casings 7 and their connections for utilizing the vapors from the crank case and radiator.

On account of the great advantage derived by the shuttle-like movements of the slide valve the device is operative in a measure, without providing the communicating chambers 9, 10, 12, 13 and 14, also I may dispense, in some instances, with the needle valve, and I do not wish to be limited to the use of these elements.

I claim as my invention,—

1. In an auxiliary carburetor, a cylindrical casing, a cylindrical receptacle within and closing one end of the casing, said receptacle being provided with annular chambers in communication with each other and having a valve seat formed in its inner end, a second cylindrical receptacle within and closing the opposite end of the casing, said second receptacle being provided with annular chambers in communication with each other and having apertures formed in its inner end, a hollow slide valve disposed within the casing to permit movements between said receptacles and having a by-pass in communication with the annular chambers of the second receptacle, a needle valve for said valve seat, said needle valve having a stem traversing the by-pass and threaded in the second cylindrical receptacle, an intake pipe having branches in communication with a chamber of the first named cylindrical receptacle, and a discharge pipe in communication with a chamber of the second cylindrical receptacle.

2. In an auxiliary carburetor, a cylindrical casing, a pair of cylindrical receptacles disposed in the ends of said casing and providing an elongated chamber between and in communication with said receptacles, one of said receptacles being provided with a valve seat, a slide valve having a by-pass disposed in said elongated chamber, a needle valve for said valve seat having a stem mounted

on one of the receptacles of said pair and traversing the by-pass, an intake pipe having branches communicating with one of said receptacles, and a discharge pipe communicating with the other receptacle of said pair. 70

3. In an auxiliary carburetor, a casing, a pair of receptacles disposed in the ends of said casing and providing an elongated chamber between and communicating with said receptacles, one of the receptacles of said pair being provided with a valve seat and a plurality of intake pipes, the other receptacle of said pair being provided with a discharge pipe, a slide valve having a by-pass and disposed in said elongated chamber, 80 and a needle valve for said valve seat having a stem threaded in one of the receptacles of said pair and traversing said by-pass.

4. In an auxiliary carburetor, the combination with a casing having an intake port and a discharge port near its ends, of a pair of receptacles closing the ends of the casing and providing an elongated chamber between said receptacles, each receptacle having ports communicating with said chamber and one of said receptacles having a valve seat, a needle valve for said valve seat having a stem traversing said chamber, and an apertured slide valve having a by-pass 90 receiving the stem of the needle valve and disposed loosely in said chamber to permit it to be moved by the suction of the engine. 95

5. In an auxiliary carburetor, the combination with a casing closed at its respective ends and having an apertured partition adjacent to one of its ends, a discharge pipe communicating with that end of the casing outwardly of said apertured partition, a slide valve in the casing having a by-pass and having an aperture in one of its ends communicating with the by-pass, an intake pipe communicating with the closed end of the casing opposite to said apertured partition for conducting a fuel mixture to said casing for moving the slide valve into engagement with said partition to obstruct a part of the areas of the apertures of said partition. 105 110

6. In an auxiliary carburetor an upright casing, an apertured receptacle having a valve seat and mounted in the lower end of the casing, an apertured receptacle normally in communication with the first named receptacle and mounted in the upper end of the casing, a slide valve for said valve seat having a stem threaded in the upper receptacle and engaging in said by-pass, a discharge pipe communicating with the upper receptacle, and a plurality of intake pipes communicating with the lower receptacle. 115 120 125

7. In an auxiliary carburetor, an upright casing, a plurality of communicating chambers in the lower part of the casing, a plu- 130

rality of communicating chambers in the upper part of the casing in communication with the first named chambers, a slide valve loosely disposed in the casing between the lower and upper chambers and having a by-pass communicating with all of said chambers, a discharge pipe communicating with the chambers in the upper part of the

casing, and intake pipes for conducting a fuel mixture, said intake pipes being in communication with the first named chambers for moving the slide valve.

In testimony whereof, I have affixed my signature.

CLYDE M. DAWDY,
